UNITED STATES PATENT OFFICE.

OTTO A. HOKANSON, OF WOODSTOCK, ILLINOIS, ASSIGNOR TO WOODSTOCK TYPE-
WRITER COMPANY, OF WOODSTOCK, ILLINOIS, A CORPORATION OF ILLINOIS.

LETTER-SPACING MECHANISM FOR TYPEWRITERS.

Application filed November 2, 1925. Serial No. 66,140.

This invention relates to mechanism for effecting letter space movement in typewriting machine having power-actuated driving mechanism and has for its object 5 the provision of mechanism of the class named which shall be of improved construction and operation and in which the letter space movement is controlled by a member in the key board but effected by the power 10 drive.

The invention is exemplified in the combination and arrangement of parts shown in the accompanying drawings and described in the following specification and 15 it is more particularly pointed out in the appended claims.

In the drawings:

Fig. 1 is a fragmentary sectional view showing one form of letter space mechanism 20 embodying the present invention;

Fig. 2 is an elevation showing the switch mechanism for controlling the power operation of the typewriter; and

Fig. 3 is a transverse sectional view showing the switch mechanism of Fig. 2 as 25 viewed from the left in that figure.

The numeral 10 designates the frame of a typewriter having key levers 11 and type bars 12. A toothed cylinder 13 extends 30 transversely of the typewriter frame and is journaled to rotate therein. A ratchet wheel 14 is positioned outside of the right hand side plate of the typewriter frame as shown in Fig. 2 and is secured to the end of 35 the cylinder 13. A solenoid 15 is mounted on the frame 10 and is provided with a plunger 16 having a pawl 17 pivoted thereon in position to engage the ratchet wheel 14. The electric circuit which energizes the magnet 15 is connected with a pair of contact 40 members 18 and 19. The contact member 19 is carried on a lever 20 having a laterally projecting ear 21 and a downwardly projecting tail piece 22. A plate 23 is mounted 45 to slide on the tail piece 22 and is urged downwardly by a spring 24. A stop 25 limits the downward movement of the plate 23. The tail piece 22 carries a laterally projecting lug 26 which engages a lug 27 on the 50 end of an arm 28. The arm 28 is secured to a rock shaft 29 which extends transversely of the typewriter frame and is journaled 55 therein. The shaft 29 has a bar 30 fixed thereto which engages the lower faces of contact members 31 carried on the key levers

11. A spring 32 connects the lug 21 with the arm 28 and holds the bar 30 against the contact members 31 and tends to rotate the lever 20 in a counter-clockwise direction as viewed in Fig. 2. The lever 20 is normally held against rotation by the lug 27 but when a key lever is depressed the rock shaft 29 is moved to lift the projection 27 and free the lever 20 so that the contacts 18 and 19 are permitted to move into engagement and close the circuit of the solenoid 15. The lug 27 engages a projection 33 on the slide plate 23 and moves the projection upwardly by extending the spring 24. When the solenoid 15 is energized the ratchet wheel 14 and the toothed cylinder 13 will be given a limited amount of rotation in a counter-clockwise direction as viewed in the drawings. The plunger 16 is pivotally connected at 35 to a lever 36 pivotally attached at 37 on the frame 10. The lever 37 has an upwardly projecting arm 38 which moves into engagement with a pin 39 projecting inwardly from the tail piece 22. This will rotate the lever 20 in a clockwise direction to separate the contacts 18 and 19. The movement will also free the slide plate 23 so that the lug 33 will be moved by the spring 24 beneath the lug 27 thus retaining the contacts 18 and 19 in spaced relation. As soon as the key lever is released the lug 27 will slide from the projection 33 onto the lug 26 so that the parts will be restored to their initial position. In this way, a depression of any key 80 lever closes the circuit of the solenoid and effects limited rotation of the toothed cylinder 13. The circuit is automatically broken at the close of the movement of the solenoid. A lever 40 is provided for adjusting the position of the contact member 18 to control 85 the period of contact between the points 18 and 19 and thus regulate the movement of the toothed cylinder 13. A switch 41 is interposed in the electric circuit. The type bars 12 are connected by sub-levers 42 to 90 actuators 43 which are moved by the key levers 11 into engagement with the toothed cylinder 13 to actuate the type bars each time a key is depressed. The mechanism 95 thus far described is similar to that shown in my prior application, Serial Number 60,395.

A letter space bar 42 is arranged at the front of the key board in the usual manner and is provided with a stop 43 for limiting 100

its upward movement. The bar 42 is carried on arms 44 which are secured to a shaft 45 journaled in the frame. The member 46 is pivotally connected at 47 to an L-shaped link 48 which is pivotally connected at 49 to an arm 50 having a pivotal support 51 on a cross bar 52. The arm 50 has a nose piece 53 which engages the upper edge of the bar 30. It will be seen that downward movement of the space bar 42 will tend to straighten the toggle formed by the link 48 and the arm 50 so as to move the pivot 49 into alignment with the pivot points 47 and 51. This will depress the bar 30 and energize the solenoid 15 in the manner previously described. The arm 50 is provided with a contact member 53 which engages a projection 54 on the adjacent actuator 43 and moves the actuator into engagement with the toothed cylinder 13 so that when the cylinder is rotated by the solenoid 15 the actuator 43 will be moved forwardly. The actuator 43 corresponding to the arm 50 is pivotally connected at 55 to an arm 56 pivotally mounted at 51 on the cross bar 52. A link 57 connects the arm 55 with an arm 58 secured to a shaft 59 journaled in brackets 60 mounted on the cross bar 52. A link 61 extends rearwardly from the arm 58 and is provided with a slot 62 which engages a pin 63 on a dog rocket 64 for controlling the escapement wheel 65 of the platen feed mechanism. It will be seen that the slot 62 will permit the oscillation of the dog rocket 64 during the ordinary operation of the typewriter but that the dog rocket will also be operated when the space bar 42 is depressed to energize the solenoid and move the link 61 forwardly through the movement of the actuator 43. The letter spacing operation is controlled by the space bar 42 but the energy for effecting the operation is furnished by the solenoid 15.

I claim:

1. The combination with a typewriter having escapement mechanism, of electrically energized means for operating said escapement mechanism, a rock shaft journaled in the frame of said typewriter, arms projecting forwardly from said rock shaft, a letter space bar supported on said arms, an arm extending upwardly from said rock shaft, a pair of toggle links extending rearwardly from said upwardly projecting arm and connected therewith, and switch mechanism for controlling said solenoid, said switch mechanism being operated by said toggle links when said space bar is depressed.

2. In a typewriter, a rotary toothed member, a solenoid, an electrical circuit for energizing said solenoid, means operated by said solenoid when energized for imparting a limited rotary movement to said toothed member, letter spacing mechanism, an ac-

tuator movable into engagement with said toothed member and operable by said toothed member for moving said letter space mechanism to effect a single letter space movement of said typewriter, a letter space key, a rock shaft disposed adjacent the key board of said typewriter and connected with said letter space key so that depression of said letter space key effects a partial rotation of said rock shaft, an arm connected with said rock shaft, a pair of toggle links, one of which is connected to said arm, said toggle links extending rearwardly from said arm and arranged to move downwardly when said rock shaft is operated, and means operated by said toggle links for closing the circuit of said solenoid.

3. In a typewriter having type keys and letter space mechanism, a rotary toothed member, a solenoid for imparting limited rotary movement to said toothed member, an electric circuit for energizing said solenoid, an actuator for said letter space mechanism arranged to engage said toothed member, a horizontally extending pivoted link having means thereon for moving said actuator into engagement with said toothed member, a rock shaft extending transversely of said typewriter adjacent the key board thereof, a space bar for operating said rock shaft, means connecting said rock shaft and link to move said link and effect operative connection between said actuator and toothed member when said space bar is depressed, and means operated by said space bar for closing said solenoid circuit subsequent to the movement of said actuator into operative engagement with said toothed member.

4. In a typewriter having type keys and letter space mechanism, a rotary toothed member, an actuator for said letter space mechanism movable into engagement with said toothed member, a horizontally extending link pivoted adjacent its rear end and having means thereon for moving said actuator into engagement with said toothed member, a rock shaft extending transversely of said typewriter adjacent the key board thereof, an arm extending upwardly from said rock shaft, a second link connecting the forward end of said first-named link with said arm and forming a toggle with said first-named link, a spring for holding said toggle in a bent position, a space bar for operating said rock shaft to straighten said toggle and move said actuator into engagement with said toothed member, a solenoid for operating said toothed member, a switch for controlling said solenoid, and means operated by said toggle for closing said switch subsequent to the movement of said actuator into engagement with said toothed member.

5. In a typewriter having type keys and letter space mechanism, a rotary toothed

member, an actuator for said letter space mechanism movable into engagement with said toothed member, a space bar for moving said actuator, a solenoid for imparting partial rotation to said toothed member, an electric circuit for energizing said solenoid, and switching mechanism operated by said space bar for closing said circuit, said switching mechanism comprising a pair of spaced contacts, a pivoted lever for supporting one of said contacts, a spring tending to rotate said lever to close said contacts, a fixed and a movable stop on said lever, a detent normally engaging said fixed stop to hold said contacts open but movable out of engagement with said fixed stop when said space

bar is depressed, said movable stop being shiftable by said detent when said detent is moved out of engagement with said fixed stop, means operated by said solenoid for 20 engaging said lever to move said lever against the tension of the spring thereon and clear said detent from said movable stop, and a spring for returning said movable stop into the path of said detent to prevent engagement of said contacts while said space bar is held in depressed position. 25

In testimony whereof I have signed my same to this specification on this 29th day of October, A. D. 1925.

OTTO A. HOKANSON.
